Primary Examiner — Philip S Hyder(74) *Attorney, Agent, or Firm* — Saidman DesignLaw Group, LLC**CLAIM**

The ornamental design for a screen protector installation device as shown and described.

DESCRIPTION

FIG. 1 is an open front top perspective view of a screen protector installation device showing our new design;
FIG. 2 is an open front bottom perspective view thereof;
FIG. 3 is an open rear top view thereof;
FIG. 4 is an open front view thereof;
FIG. 5 is an open rear view thereof;
FIG. 6 is an open left side view thereof;
FIG. 7 is an open right side view thereof;
FIG. 8 is an open top view thereof; and,
FIG. 9 is a open bottom view thereof.
The broken lines and the portions within illustrate structure or features which form no part of the claimed design.
